DESIGN FOR A BURIAL CASKET HANDLE

Stephen Junkunc, Jr., Oak Park, Ill., assignor to Stephen Junkunc, Sr., Oak Park, Ill.

Application July 27, 1939, Serial No. 86,273

Term of patent 14 years

To all whom it may concern:

Be it known that I, Stephen Junkunc, Jr., a citizen of the United States, residing in Oak Park, in the county of Cook, State of Illinois, have invented a new, original, and ornamental Design for Burial Casket Handles, of which the following is a specification, reference being had to the accompanying drawing, forming part thereof.

Figure 1 of the drawing is a front view of a burial casket handle embodying my design; Figure 2 is a bottom edge view of the handle shown in Figure 1; and Figure 3 is a section taken on line 3—3 of Figure 1.

I claim:

The ornamental design for a burial casket handle, as shown.

STEPHEN JUNKUNC, JR.
